UNITED STATES PATENT OFFICE

MILLARD COLE SPENCER, OF EAST ORANGE, NEW JERSEY, ASSIGNOR TO CROCKER-WHEELER ELECTRIC MANUFACTURING COMPANY, OF AMPERE, NEW JERSEY, A CORPORATION OF NEW JERSEY

ELECTRICAL SWITCH

Application filed October 26, 1926. Serial No. 144,246.

In the operation of gas-electric vehicles, an engine drives an electric generator, and the generator supplies current to the motor which propels the vehicle. Control of speed 5 may be wholly through the control of gas to the engine and the brakes, provided that there are suitable automatic means for preventing excessive current flow from the generator to the motor.

10 The object of this invention is to provide such automatic means in the form of a solenoid operated switch suitable for operation by the current flowing from the generator to the motor, and for controlling the shunt field of 15 the generator. Further objects are to provide a switch which is sensitive and reliable in its automatic action and which will be brought to a definite position by a definite flow of the operating current regardless of 20 whether the definite flow has followed a greater or a lesser flow. A further object is to provide a regulating system which will be smooth in its action so that excessive surges of current will be avoided and acceleration 25 without undue shock will be insured. A further object is to provide a switch the operation of which will not be influenced by the jolting or other abrupt movements of the vehicle.

30 In the accompanying two sheets of drawings which form a part of this description,

Figure 1 is a plan view of a switch which embodies this invention, the top cross bar being broken away.

35 Fig. 2 is an elevation of the same.

Fig. 3 is a section through the comb of contact fingers and the support therefor.

Fig. 4 is a diagram of the circuits.

The switch comprises a frame 10 which 40 carries a shaft 11. Two solenoid coils 12, 12 are supported by the frame. They are disposed along arcs of a circle and on opposite sides of the circle. Armature cores 13, 13 in balanced relation are carried by arms 14, 14 45 from the shaft. On the shaft are a series of coiled springs 15, 15 which are preferably quite limber and held nearly wound up and therefor under initial tension by a bar 16 which is carried by the shaft. Throughout 50 the operative movement of each spring its

tension remains substantially uniform. A support 17 of insulating material carries a comb of spring fingers 18, 18 which rest on contact buttons 19, 19. A bar 20 limits the lift of the fingers away from the contact buttons. The support for the comb of spring fingers and the contact buttons is set at an angle to the axis of the shaft, so that as the shaft turns the ends of coiled springs carried by the shaft will engage and lift the contact fingers successively. The initial tension of the coiled springs is greater than that of the contact fingers. In consequence, each finger on being engaged, if there is sufficient force to lift it, will be at once fully 55 lifted against the limiting bar and not left in hesitating contact. During any further movement of the shaft in the same direction after the contact finger has been lifted, the end of the coiled spring remains in engagement with the tip of the contact finger and alone yields.

Leads 21, 21 connect the comb of contact fingers and the contact buttons with blocks of resistances 22, 22 in series with the shunt 75 field 23 of the generator. Current is led from the armature 24 of the generator through the solenoid coils of the switch and thence to the vehicle motor 25.

In operation, with the engine turning over 80 slowly substantially no voltage will be generated and the vehicle will be held if necessary by its brakes when a temporary stop is being made. To start up, the brakes are released and the engine is speeded up. Current is at 85 once generated and the generator field strongly excited. To prevent the current from reaching an excessive value before the vehicle has had time to get underway and its motor has had sufficient time to build up a 90 sufficient counter electromotive force is the purpose of the switch. This is effected by the flow through the actuating solenoids which causes the blocks of resistance to be inserted in series in the generator field circuit, thereby weakening the field and keeping the current generated down to a proper value. As the vehicle speeds up and the counter electromotive force of the motor increases the current tends to decrease. This decrease in 95 100

current through the solenoid coils of the switch cuts out resistance in the field circuit of the generator thereby increasing the generator voltage and tending to maintain the current. In this way rapid acceleration of the vehicle is obtained.

In ascending a grade the vehicle slows up and the counter electromotive force of the motor decreases and the motor tends to draw an excessive current from the generator and stall the engine. This increase in current through the switch solenoids actuates the switch and inserts resistance in the field circuit of the generator. This cuts down the generated voltage and limits the current to a desired value which will not overtax the engine.

I claim:

1. In an electrical switch, an electrical switch member having a series of consecutive positions at which different electrical circuit connections are made and broken, a series of springs held under initial tension, and means for consecutively engaging the springs by the switch in passing between each switching position, each spring being continued in engagement to the limit of the switch movement and further tensioned.

2. In an electrical switch, an electrical switch member having a series of contact fingers and contact buttons engaged thereby, a shaft, and springs under initial tension carried by the shaft for actuating the fingers at different angular positions of the shaft.

3. In an electrical switch, a series of interconnected spring contact fingers and contact buttons engaged thereby, a shaft, and springs under initial tension carried by the shaft for engaging the contact fingers at different angular positions of the shaft and lifting the fingers from the buttons.

MILLARD COLE SPENCER.
